CLOTHESPOLE

Ersyl F. Chambliss, Chicago, Ill., assignor of one-half to Joseph W. Fay, Villa Park, Ill.

Application November 22, 1934, Serial No. 754,330

7 Claims. (Cl. 211—123)

My invention relates to clothes-poles such as are arranged across clothes closets from one wall to another and attached at opposite ends to the molding strips or cleats with which the walls of the closet are provided.

Extensible devices of this character for employment in closets of varied widths have been provided before, but the mountings for these devices either have not provided the requisite strength or have been difficult to attach, or, when attached, were impossible to remove without mutilating or destroying the attachment means.

The object of my present invention is to provide an extensible device of the character above described with improved means for attaching the ends of the device to the molding strips or cleats with which the walls of the closet are provided, which improved means will provide attachments of requisite strength and attachments which may be readily applied, and at the same time are adapted to be readily removed without mutilating or destroying the attachment means or pole.

Further objects and the features and advantages of the invention will be apparent from the following detailed description taken in connection with the accompanying drawing, in which:

Figure 1 is a perspective view of a device embodying the present invention, showing fragmentarily at one end a section of one of the closet walls supporting one end of the device;

Figure 2 is a fragmentary side elevational view of one end of the pole shown in Figure 1, showing the attachment means therefor; and

Figure 3 is a vertical section taken on the line 3—3 of Figure 2.

In the illustrated embodiment of the invention, 5—5 designate the opposite walls of a closet; 6—6 supporting strips, such as molding or hook-strips secured to the walls; and 7 the improved extensible clothes-pole.

The extensible clothes-pole 7 is shown as comprising telescopically related sections in the form of tubes 8 and 9 equipped with means 10 and 11, respectively, for attaching the ends of the pole to the supporting strips 6. The attaching means at 10 and 11 are of the same form and construction, and are applied to the tubular members 8 and 9 in the same manner, so that a description 50 of one will suffice for both.

Describing the attachment means at 10, it consists of a sheet metal cap 12 having an end wall 13 and an annular flange 14 receiving telescopically the adjacent end of the tube 8. The end 55 of the tube fitting within the flange 14 has in-

tegral tabs 15 which extend through diametrically opposite arcuate openings 16 in the end wall 13, and are turned over and clinched firmly to the wall 13 rigidly to join the cap to the tube. It is to be understood that the invention may employ other means than the means shown for rigidly securing the outer ends of the tubes 8 and 9 to the respective caps 12. The opposite end of the outer tube 8 may be finished by means of a ferrule 17.

The cap 12 is provided with a wood screw 18, the shank of which passes through the center of the end wall 13 and extends axially from the end of the pole. The head of the screw 18 is disposed internally of the annular flange 14 at 15 19, and the screw is rigidly joined to the cap 12, for example, by upsetting the shank radially outwardly at 20 to secure the wall 13 between the upset portion 20 and the head 19. Other means may be employed for rigidly joining the screw 18 to the cap 12. Adjacent its headed end the screw 18 has a square or non-circular neck 21 which locks the screw against rotation with respect to the cap 12.

To provide leverage means for tightening the 25 screws 18 into place, the flange 14, of each cap 12, has a pair of integral and diametrically opposite wings 24. These wings 24 are turned or bent out to extend radially from the adjacent pole section, and the opposite vertical edges of 30 these wings have flanges turned outwardly at 25 to form finger-pieces suitable to be grasped between the fingers. The finger pieces 24 are joined to the flanges 14 by connecting portions 26 which, preferably, widen toward the flanges 14 35 to provide adequate strength.

In applying the pole, its sections 8 and 9 are extended between the molding or hook-strips 6 on opposite walls 5 until the screws 18 are engaged with the strips 6 sufficiently so that upon 40 turning the screws, they will be threaded into these wood strips 6. The screws 18 may then be threaded into the strips 6 by grasping the pole sections 8 and 9 and turning the same, for example, in opposite directions, the screws thread- 45 ing into the strips 6 with the turning movement of the pole sections. As the caps 12, at the ends of the tubes, are brought up toward the strips 6, the finger-pieces 24 may be grasped and the screws tightened firmly into place, the finger- 50 pieces 24 providing leverage means for this purpose. These finger-pieces also provide for releasing the screws from secure attachment, and after they are released, they may be threaded out of the strips 6, or other supports, by grasp- 55

ing the pole sections and turning the same in directions opposite to the directions in which they are turned in applying the device.

I do not intend to be limited to the precise details shown or described.

I claim:

1. An extensible clothes-pole comprising telescoping pole sections and wood screws extending axially from the outer ends of said sections and joined rigidly thereto, whereby said screws may be threaded into molding strips and the like by grasping and turning the pole sections.
- 10 2. An extensible clothes-pole comprising telescoping pole sections, wood screws extending axially from the outer ends of said sections and joined rigidly thereto, whereby said screws may be threaded into molding strips and the like by grasping and turning the pole sections, and radially extending finger-pieces adjacent the outer 20 ends of said pole sections to provide leverage means for tightening said screws.
- 15 3. An extensible clothes-pole comprising telescoping pole sections, cap members rigidly secured to the outer ends of said pole sections, and 25 wood screws extending axially from the outer ends of the pole sections and joined rigidly to said cap members, whereby said screws may be threaded into molding strips and the like by grasping and turning the pole sections.
- 20 4. An extensible clothes-pole comprising telescoping pole sections, cap members rigidly secured to the outer ends of said pole sections, wood 30 screws extending axially from the outer ends of the pole sections and joined rigidly to said cap members, whereby said screws may be threaded into molding strips and the like by grasping and turning the pole sections, and finger-pieces formed integral with the outer ends of said pole sections to provide leverage means for tightening said screws.
- 35 5. An extensible clothes-pole comprising telescoping tubular pole sections, cap members having end walls adjacent and annular flanges fit- 40

ting over the outer ends of said pole sections, tabs on the outer ends of said pole sections and fitting through openings in the end walls of said cap members and turned over and clinched to said cap members, wood screws having shanks passing through the centers of the end walls of said cap members and extending axially from the opposite ends of the pole, said screws having abutments on opposite sides of said end walls for securing the screws thereto, and polygonal necks between said abutments for preventing relative turning movement between the screws and the pole sections.

5 6. An extensible clothes-pole comprising telescoping tubular pole sections, cap members having end walls adjacent and annular flanges fitting over the outer ends of said pole sections, tabs on the outer ends of said pole sections and fitting through openings in the end walls of said 10 cap members and turned over and clinched to said cap members, wood screws having shanks passing through the centers of the end walls of said cap members and extending axially from the opposite ends of the pole, said screws having abutments on opposite sides of said end walls 15 for securing the screws thereto, polygonal necks between said abutments for preventing relative turning movement between the screws and the pole sections, and finger-pieces formed integral with the annular flanges of said cap members 20 and extending radially from the opposite ends of the pole sections.

25 7. An extensible clothes-pole comprising telescoping pole sections, cap members rigidly secured to the outer ends of said pole sections, wood screws extending axially from the outer ends of the pole sections and joined rigidly to said cap members, whereby said screws may be threaded into molding strips and the like by grasping and turning the pole sections, and leverage means formed integral with said cap members for tightening said screws.

ERSYLF. CHAMBLESS.
